UNITED STATES PATENT OFFICE.

REGINALD A. FESSENDEN, OF CHESTNUT HILL, MASSACHUSETTS. ASSIGNOR TO SUB-MARINE SIGNAL COMPANY, OF PORTLAND, MAINE, A CORPORATION OF MAINE.

METHOD FOR ELIMINATING UNDESIRED IMPULSES.

Application filed November 10, 1920. Serial No. 423,184.

To all whom it may concern:

Be it known that I, REGINALD A. FESSENDEN, of Chestnut Hill, in the county of Middlesex and State of Massachusetts, a citizen of the United States, have invented new and useful Improvements in Methods for Eliminating Undesired Impulses, of which the following is a specification.

My invention relates to methods and apparatus for eliminating undesired impulses and more particularly to eliminating disturbing impulses, such as noises and static in signaling circuits.

My invention has for its object greater efficiency in the elimination of such disturbing impulses and more particularly greater efficiency in signal reception.

Figures 1, 2, 3, 4 and 5 show, partly diagrammatically, arrangements suitable for carrying out my invention.

In Fig. 1, 14 is an antenna grounded at 25. The circuits 14, 12, 16, 18, 21, 25 and 14, 13, 17, 19, 22, 25 are both tuned to the desired signals, the inductance 16 being larger than the inductance 17 and the capacity 18 being less than the capacity 19.

21 and 22 are any receiving devices, for example the filaments of two filament galvanometers, connected so that their indications or movements are in opposite directions, as shown by the arrows, and oppose each other, effected, for example, in the case of the filaments, by joining them with a light bar 24.

On the reception of a mixture of desired signals and undesired impulses on the antenna 14, the desired signals will divide substantially evenly between the two circuits and there will be no movement of the bar 24.

Undesired impulses received on the antenna 14 will, however, distribute themselves unevenly between the two circuits on account of the different amounts of inductance and capacity in the two circuits, and consequently will produce a movement of the bar 24, a record of which (27) is shown in Fig. 2.

14, 15, 20 and 25 is a third circuit which is substantially untuned and contains the adjustable ohmic resistance 15, and the galvanometer filament 20.

Consequently the indication produced by the galvanometer filament 20 if it were free would be that represented by the record 26

in Fig. 2 if the signal D, represented by the dash 40 and the dots 41, 42, were received and also the impulse 29.

It will be seen that if two records are compared—i. e., the record 27 made by the bar 24 and the record 26 made by the filament 20, the fact that 29 is a disturbing impulse and not a signal is at once apparent and the message can be read.

This may also be done directly by attaching the filament 20 to the bar 24 by a second bar 23 in such a direction that the motions are opposed to each other, as shown by the arrows.

In this case the record produced by the motion of the combined bar will be as shown in 28, Fig. 2, where the undesired impulse 31 is substantially cut out.

In Fig. 3 is shown a variation of this method, in which 33, 33' are circuits tuned to the desired signals and 32, 32' are circuits tuned to a frequency below that of the desired signals and 34, 34' circuits tuned to a frequency above that of the desired signals. 45, 46, are galvanometer filaments tending to move in the direction of the arrows and connected by the bar 47 and grounded at 35.

In this case the filament 46 will be acted on by a force produced substantially only by the undesired impulses, since substantially all the desired signals will be led to ground without affecting the filament 46. On the other hand the filament 46 will be acted upon by a force due to the sum of the undesired impulses and the desired signals. Consequently, since the filaments are connected together by the bar 46 and tend to move in opposite direction, the resultant motion of the bar 47 sideways will be due to the signals alone.

Fig. 4 shows another modification in which the circuits 32, 32', 33, 33', 34, 34' and the filaments are as stated above, but the circuit 33', instead of being connected to ground, is connected through a resistance 48 to the galvanometer filament 46. This ohmic resistance 46 is preferably made to have such value that the circuit 33', 48 is largely dead beat to the desired signals, so that substantially all, or a large part, of the energy of the desired signals is absorbed in this circuit, whereas it is not so largely absorbed in the circuit 33.

For the sake of simplicity I have shown 110

the device for opposing and comparing the signals and desired impulses in the form of filament galvanometer, though it will be readily understood by those skilled in the art that many other equivalent devices may be used—for example transformers with opposing primaries and secondaries—and that the signals may be audible instead of visual or mechanical.

10 In Fig. 5, the circuits, comprising the inductances 16, 17, 16', 17', capacities 18, 19, 18', 19', resistances 50, 51, 50', 51', transformer primaries 53, 54, 53', 54', and grounds 35, 35, are all tuned to the desired signals, but the circuits containing the inductances 16 and 16' have more inductance and less capacity than the circuits containing the inductances 17 and 17'.

15 The resistances 50, 51, 50', 51' are all originally equal but the resistances 50' and 51 are variable.

20 The circuit containing the transformer secondaries 55, 55' and the indicating instrument 56 is connected so that the transformer primaries 53, 54 oppose their effect on the secondary 55 and the transformer primaries 53', 54' oppose their effect on the secondary 55'.

25 In operation the desired signals are first sent and the circuits adjusted until no signal is detected in the detector 56.

30 Then the undesired disturbing impulses are listened in to and the circuits adjusted until no indication is produced in this case also on the indicator 56.

I. e., neither desired signal or the undesired impulses produce any indication on 56.

Then the resistance 50' is slightly altered

and this will make a comparatively small difference in the effect of the undesired impulses compared to what it will on the effect of the desired signals and consequently the indication produced by 56 will be mainly due to the desired signals, especially if 51 is also altered, to balance out the remainder of the undesired impulses.

40 It will, of course, be understood that a number of such sets of devices may be used in series with each other, thereby producing a successive strengthening of the ratio 50 of the desired signals to the undesired impulses, and also other instruments well known in the art, for example amplifiers, may also be used.

45 The object of making the resistance 51, Fig. 1, variable is to assist in balancing the opposing indications. This may also be done by any equivalent means—for example by inserting adjustable amplifiers in the circuits 16, 18 and 17, 19.

50 What I claim is:

55 In a system of signaling, the method of eliminating disturbing noises, which consists in receiving the disturbing noises more effectively than the signals which it is desired to receive, on one portion of the receiving system, recording the indications as received, and receiving said disturbing noises and desired signals in a more equally effective manner on another portion of said receiving system, and recording the indications so received, and detecting and eliminating the disturbing effects by comparison of said records.

60 REGINALD A. FESSENDEN.
